UNITED STATES PATENT OFFICE.

CHARLES GEORGE JOHNSON, OF SAULT STE. MARIE, MICHIGAN.

SIGNAL FOR LOCATING SUNKEN VESSELS.

1,206,713.

Specification of Letters Patent. Patented Nov. 28, 1916.

Application filed July 17, 1914, Serial No. 851,559. Renewed October 13, 1916. Serial No. 125,501.

To all whom it may concern:

Be it known that I, CHARLES GEORGE JOHNSON, a citizen of the United States, residing at Sault Ste. Marie, in the county of 5 Chippewa and State of Michigan, have invented certain new and useful Improvements in Signals for Locating Sunken Vessels, of which the following is a specification.

10 The present invention relates to certain new and useful improvements in signals and more particularly to devices of this character which may be utilized to designate the location of sunken vessels, so that 15 upon sighting the signal passing vessels will be warned of the location of the sunken vessel and may steer clear of the same to prevent fouling it, and has for its object to provide a device of this character which 20 will float upon the surface of the water above the sunken vessel and provide suitable day and night signals.

A further object of the invention is to provide a device which under normal conditions is positive in operation, and which 25 may be utilized in cases of necessity as a life buoy.

A still further object is to provide a device of this character which is comparatively simple and inexpensive in its construction, and which will not easily get out 30 of repair.

With these and other objects in view, the 35 invention consists in certain novel combinations and arrangements of the parts as will more fully appear as the description proceeds, the novel features thereof being pointed out in the appended claims.

For a full understanding of the invention, reference is to be had to the following 40 description and accompanying drawing, in which:—

Figure 1 is a side elevation of the device in operation, showing the stern of a sunken 45 vessel and the floating signal on the surface of the water above the vessel. Fig. 2 is a side elevation of the device in its inoperative position. Fig. 3 is a transverse sectional view through the same, and Fig. 4 is a 50 horizontal sectional view on the line 4—4 of Fig. 2.

Corresponding and like parts are referred to in the following description and indicated in all the views of the drawing by 55 the same reference characters.

Specifically describing the invention, the

numeral 1 designates the deck of a vessel upon which is mounted, at any suitable point, a cradle or support 2 adapted to detachably support a signal 3 when the same 60 is in an inoperative position. The cradle 2 is formed of four upright pieces of angle iron 4, which serve as corner posts, connected at their bases by angle irons 5 which are permanently fastened to the deck 1 of the 65 vessel by suitable fastening members 6, thereby forming a substantially square frame. Fastened to the upper extremities of opposite corner posts 4 and extending downwardly along opposite sides of the 70 cradle 2 are the angle irons 7 which converge toward each other so as to form a substantially V shaped seat upon which the floating signal rests under normal conditions, and are fastened together at their 75 lower extremities by the plates 8, which are in turn secured to the angle irons 5 at the base of the cradle 2. The angles of the angle irons 7 face the inside of the cradle so that the outer flanges 7^a thereof serve to 80 prevent the signal member 3 from being jarred out of the cradle by the motion of the ship upon the water.

The upper portion of the signal consists of a water tight compartment 9 which is 85 always filled with air. This compartment 9 is fitted within the upper portion of a frame 10 formed of angle iron, which frame is fastened to the compartment by suitable fastening members 11. The lower extremities 90 of the irons forming the frame 10 are inclined downwardly from the bottom of the compartment 9, and converge toward each other from opposite sides so as to form a substantially V shaped base adapted to 95 rest upon the V shaped seat of the cradle 2, and forming a frame upon which is adapted to be mounted a cable carrying means, the lower ends thereof being secured together by the plates 13. The angle formed by these 100 converging arms is substantially the same as the angle formed by the irons 7 of the cradle 2 so that the irons 12 will fit snugly upon said irons 7, and as before stated, the outer flanges 7^a of the irons 7 will serve to 105 prevent the irons 12 from jarring out of the cradle, as shown in Fig. 4.

Fastened at their opposite ends to opposite angle irons 12 and extending across opposite sides of the signal frame 10 are the 110 transverse bars or angle irons 14. Fastened to each bar 14 and at substantially the cen-

ter thereof are the journal bearings 15 in which is mounted a transverse shaft 16 which carries a reel 17 adapted to receive a suitable length of cable 18. One end of the 5 shaft 16 projects beyond the frame 10 and cradle 2 and is squared at 19 to receive a removable crank 20, shown in dotted lines, utilized in winding the cable upon the drum. One end of the cable 16 is fastened to the 10 hull of the vessel by any suitable means such as the U bolt 21, while the opposite end of the cable is fastened to the reel 17. At the lower extremities of the frame 10 are two guide rollers 18^a having their opposite ends journaled in the plates 13. These two rollers 18^a serve as guides for the cable to prevent kinking or twisting thereof when being wound upon or unwound from the reel 17. Opposite ends of the reel 17 are provided 15 with brake drums 22 around which are wound the oppositely disposed brake bands 23 which serve to retard the revolution of the drum when the cable is unwinding therefrom, and to prevent the unwinding 20 of the cable from the drum after the vessel has struck bottom so that the float 3 can not drift away. Secured to the bars 12 nearest the respective ends of the reel are the upwardly projecting brackets 24, at the 25 outer ends of which are pivoted, at intermediate points 25^a in their lengths, the levers 25. One end 26 of each of the levers 25 is connected to one end of its adjacent brake band 23, while the opposite ends of the levers are connected to springs 27 which in 30 turn are fastened to the bottom of the compartment 9. The ends of the brake bands opposite those fastened to the lever at 26 are fastened to the upwardly projecting brackets 24. The springs 27 tend to pull upwardly on one end of the levers 25, which, owing to the lever being pivoted at 25^a, exerts a downward pressure upon the opposite ends of the levers 25, which in turn pull 35 upon the brake bands 23, which being permanently fastened at one end exert a pressure upon the brake drums 22 so as to retard the movement of the reel 17 in either direction. It will thus be seen that the cable 40 cannot become fouled in unwinding from the reel too rapidly, as the brake bands 23 continually exert a pressure upon the drum 17 to retard its movement, and the float 3 can not drift away from the location of the 45 sunken vessel.

Mounted upon the top of the compartment 9 and near the center thereof is an upright standard or pole 28 at the upper 50 extremity of which are mounted suitable day and night signals, such as the flag or pennant 29 and the lamp 30. In order that the water tight compartment may serve as a life buoy in case of necessity, as well as a signal, a rail 31 is provided at the top of the compartment 9 and another rail 32 is

provided on the sides of the compartment at substantially the center of its height. If shipwrecked persons are unable to reach a life boat or other means of support, they may grasp the rails 31 and 32 of the floating 70 buoy 9, and owing to its buoyancy will be supported thereby until they are rescued.

The cradle 2 has been described as being above deck, but if desired it may be placed below the deck with its top flush therewith, 75 as indicated by the dotted lines A in Figs. 2 and 3, so that only the buoyant signal 3 will be above the deck. The lamp 30 should always be lighted at night so that should the vessel sink in the night, the light 30 may 80 be seen by the shipwrecked persons and passing vessels. In the day time the pennant 29 serves as a signal.

In the operation of the device as the vessel sinks and the deck passes below the surface of the water the buoy 9, being water tight and filled with air, floats upon the water. As the vessel moves downward the cable 18 is unwound from the reel 17, as one end of the cable is fastened to the deck of 90 the ship. When the ship has reached the bottom of the body of water, the buoy 9 is anchored to the vessel, by means of the cable 18, and the floating buoy 9 with its signals 29 and 30 serves to designate the exact location of the sunken vessel. If desired a signal buoy may be placed upon both the bow and stern of the vessel, so that the location thereof is defined still more accurately. After the ship has sunk unfortunates who 100 were unable to reach life boats or other means of support still have this floating buoy which cannot drift away from the wreck, owing to its being fastened thereto by the cable. It will thus be seen that this 105 device serves admirably the principal purpose for which it was designed, as a signal, as well as a life buoy for saving the lives of shipwrecked persons.

Having thus described the invention, what 110 I claim as new and desire to secure by Letters Patent, is:

1. A signal for locating a vessel after it is sunk including a buoy adapted to float upon the water, said buoy being provided with a substantially V-shaped base, a cradle mounted upon the vessel and provided with a substantially V-shaped seat upon which the V-shaped base of the buoy is adapted to removably rest under normal conditions, said V-shaped seat being provided on opposite sides thereof with upstanding flanges to prevent the buoy from jarring or slipping out of the cradle, and means for anchoring the buoy to the sunken vessel to 120 prevent said buoy from drifting.

2. A signal for locating a vessel after it is sunk, including a buoy adapted to float upon the water, said buoy being provided with suitable day and night signals, the up- 130

per portion of said buoy consisting of a water tight compartment, while the lower portion thereof consists of a frame forming a substantially V-shaped base, a reel mounted upon said frame adapted to receive a suitable length of cable, one end of said cable being fastened to the vessel while the opposite end thereof is fastened to the reel, said cable being adapted to be unwound from the reel as the vessel sinks, braking means for preventing the cable from unwinding from the reel after the vessel has reached bottom, cable guide rollers mounted upon the buoy, and a cradle upon the vessel 10 provided with a substantially V-shaped seat upon which is adapted to removably rest under normal conditions the V-shaped base of the buoy.

5 rails adapted to be grasped by shipwrecked persons, while the lower portion thereof consists of a frame forming a substantially V-shaped base, a reel mounted on said frame adapted to receive a suitable length of cable, one end of said cable being fastened to the vessel while the opposite end thereof is fastened to the reel, said cable being adapted to unwind from the reel as the vessel sinks, braking means for preventing the cable from unwinding from the reel after 15 the vessel has reached bottom, means for winding the cable upon the reel, guide rollers mounted on the buoy and a cradle carried by the vessel having a substantially V-shaped seat upon which is adapted to 20 removably rest under normal conditions the V-shaped base of the buoy.

3. A combined signal for locating a vessel after it is sunk and life buoy, including a buoy adapted to float upon the water, the upper portion of the buoy consisting of a water tight compartment provided with suitable day and night signals and

In testimony whereof I affix my signature in presence of two witnesses.

CHARLES GEORGE JOHNSON.
